WELL PACKER

Charles S. Crickmer, Dallas, Tex., assignor to
Merla Tool Company, Dallas, Tex., a firm

Application July 7, 1938, Serial No. 217,960

10 Claims. (Cl. 166—12)

This invention relates to new and useful improvements in well packers.

One object of the invention is to provide an improved packer for sealing off the annular space between a well tubing and a well casing and which is constructed so that it may be rapidly lowered through the liquid in the well casing, whereby it may be moved into position and set in a minimum length of time.

Another object of the invention is to provide an improved well packer wherein are amplified passages for by-passing fluid as the packer is lowered therethrough, the passages being arranged to be automatically closed when the packer is set into sealing position, whereby the usual metallic seat and valve for closing the by-pass, together with the disadvantages of said valve and seat are eliminated.

An important object of the invention is to provide an improved well packer having a packing element with vertical channels or passages formed in its inner wall, through which the fluid may by-pass when the element is in an undistorted or normal position; said passages being closed when the element is distorted into sealing position, whereby closure of the by-pass is accomplished at the same time that the element is moved into sealing position.

A further object of the invention is to provide a device of the character described, wherein an elongate packing sleeve is mounted on its support and has by-pass channels formed in the wall of its bore, the sleeve having a plurality of reinforcing members embedded therein in spaced relation, whereby when the sleeve is distorted, the reinforcing members cause distortion in such manner as to give the sealing effect of a plurality of superposed packing elements; the provision of the channels in the wall of the bore of the sleeve permitting distortion in an inward direction, whereby the inner wall of the sleeve is moved into sealing engagement with the support and the channels are closed when the sleeve is moved into sealing position.

A construction designed to carry out the invention will be hereinafter described, together with other features of the invention.

The invention will be more readily understood from a reading of the following specification and by reference to the accompanying drawings, in which an example of the invention is shown, and wherein:

Figure 1 is a view, partly in section and partly in elevation of a well packer, constructed in accordance with the invention and showing the

same in an unset position as it is lowered through the well tubing.

Figure 2 is a similar view within the packer in its set position.

Figure 3 is an enlarged, transverse, vertical, 5 sectional view of the packing element and its associate parts.

Figure 4 is a horizontal, cross-sectional view, taken on the line 4—4 of Figure 1.

Figure 5 is a horizontal, cross-sectional view, 10 taken on the line 5—5 of Figure 1.

Figure 6 is a horizontal, cross-sectional view, taken on the line 6—6 of Figure 1.

Figure 7 is a horizontal, cross-sectional view, taken on the line 7—7 of Figure 1, and 15

Figure 8 is a horizontal, cross-sectional view, taken on the line 8—8 of Figure 2.

In the drawings, the numeral 10 designates an elongate tubular mandrel which is provided with external screw threads at its upper and 20 lower ends. The upper end of the mandrel is threaded into an elongate coupling collar 11 which has the upper end of its bore internally screw threaded at 12, whereby said collar may be connected to the well tubing A. The provision of the screw threads at the lower end of the mandrel permit said mandrel to be readily 25 connected to the well tubing A by the usual coupling collar 13.

The coupling collar 11 at the upper end of 30 the mandrel is enlarged at its lower end to form a depending annular skirt 14. The inner diameter or bore of the skirt is greater than the outer diameter of the mandrel 10, whereby an annular space 15 is formed between the skirt 35 and the mandrel. The extreme lower end of the skirt 14 is reduced to form an annular lip 16.

An elongate packing element or sleeve 17 surrounds the mandrel 10 and has its upper, reduced end confined within the lip 16 of the skirt 40 14. The wall of the bore of said sleeve is provided with a plurality of vertical channels or grooves 18 which extend throughout the entire length of the packing element, and, as is clearly shown in Figure 1, the upper ends of the 45 channels 18 communicate with the annular space 15 which is formed between the skirt 14 and the mandrel 10. The lower end of the packing element is reduced and confined within an upwardly extending annular lip 19 which is formed 50 at the upper end of a supporting cone 20. The cone surrounds the mandrel and is slideable vertically thereon, being supported on an external annular shoulder 21 which is formed on said mandrel. The bore 20' on the cone 20 is enlarged 55

at its upper portion, whereby an annular space 22 is formed between the bore of said cone and the outer surface of the mandrel 10. This annular space communicates with the lower end 5 of the vertical channels or passages 18 which are provided on the inner wall of the packing element 17. With the above arrangement, it will be manifest that a communication between the annular space 22 within the cone 20 and the 10 annular space 15 within the skirt 14 is established through the vertical channels 18.

The packing element is confined between the skirt 14 and the cone 20 and said element has a plurality of rings 23, preferably of metal, embedded therein. The rings are spaced throughout the vertical length of the packing element or sleeve and serve not only to reinforce said element but also to cause the same to be distorted in such manner as to give the effect of a plurality 15 of packing elements, as will be explained. The packing element 17 may be constructed of rubber, rubber compound or other flexible packing material.

For by-passing the fluid through the channels 25 or grooves 18 of the packing element, the cone 20 is formed with a plurality of radial openings 24 which extend inwardly through the wall of the cone and which communicate with the annular space 22 at the upper portion of the bore of 30 said cone. The annular skirt 14 at the upper end of the packing element is also formed with a plurality of radial openings 25 which extend through the skirt and which communicate with the annular space 15 within said skirt. It is 35 preferable that the openings 25 be inclined so that the flow therethrough is directed upwardly. With this arrangement, when the device is lowered into a well casing B and through the well fluid standing therein, said well fluid may flow 40 through the ports or openings 24 and into the annular space 22, from where it may flow upwardly through the channels or grooves 18 provided on the inner wall of the packing element 17. From the channels 18, the fluid enters the 45 annular space 15 and then escapes through the inclined opening 25 in the skirt. In this manner, it is manifest that the well fluid may readily by-pass the packing element when the same is in a normal, or undistorted position.

Any suitable means may be employed for setting the device within the well casing B, but for 50 purposes of illustration, a plurality of gripping slips 26 are shown. The slips are slideable on the outer surface of the cone 20 and any desired 55 number may be employed. Each slip is carried by a flexible member 27 which has its upper end engaged in a recess 28' provided in the rear face of the slip. This upper end of the supporting member 27 is pivotally secured to the slip by a 60 pin 28. The supporting member extends downwardly from the slip and is pivoted on a pin 29 which is located within a slot 30 formed in the upper end of an elongate sleeve 31, which sleeve is separate from the cone 20 and is slideable on 65 the mandrel 10. The lower end of the supporting member 27 engages the curved lower end 30' of its respective slot 30. A plurality of flat 70 friction springs 32 are mounted on the elongate sleeve 31 and have their outer surfaces curved so as to engage the wall of the well casing B.

For connecting the sleeve 31 to the mandrel 10 so that said mandrel and sleeve will move simultaneously and also for holding the slips 26 at the lower end of the cone 20 in a retracted position, 75 said sleeve is formed with an inverted J-slot 33.

A radial pin 34 extends outwardly from the mandrel and is arranged to engage within the slot 33. When the pin is engaged in the horizontal leg 33' of the J-slot, the sleeve is in such position with relation to the cone 20, that the slips 26 are held in their lowermost position on said cone (Figure 1), whereby said slips are retracted from the wall of the well casing.

In the operation of the device, the mandrel 10 is connected in the well tubing A and is lowered 10 therewith through the well casing B. The cone 20 is supported on the external shoulder 21 and the packing element is in the position shown in Figures 1 and 3, which is its normal undistorted position. The slips 26 are in their retracted position being held so by the engagement of the radial pin 34 in the J-slot 33 of the sleeve 31. As explained, the slips are connected to the sleeve 31 by the supporting member 27. As the device is lowered through the well casing B, the parts 15 maintain their same relative position and the well fluid which may be present in the casing may readily by-pass the packing element 17. This by-passing occurs not only around the exterior of 20 the packing element but also through the openings 24 of the cone and through the vertical channels 18 formed on the inner surface of the packing element. From the channels 18 the well fluid passes upwardly through the inclined ports 25 in the skirt 14 and then upwardly in the casing 30 above the packing element. By providing the by-pass channels 18, there is practically no resistance offered by the well fluid as the device is lowered into the well casing B.

When the point that it is desired to set the 35 packer is reached, it is only necessary to rotate the mandrel 10 in a counterclockwise direction so that the pin 34 on the mandrel 10 will ride out of the horizontal leg 33' of the J-slot 33 and into alignment with the vertical leg thereof. 40 When this occurs, a continued lowering of the mandrel will cause the pin to ride downwardly through the vertical leg of the J-slot. At this time the sleeve 31, as well as the slips 26 which are fastened thereto by means of the members 27 are held stationary by the friction springs 32. Therefore, as the mandrel and cone 20 carried 45 thereby, packing element 17 and the collar 11, move downwardly with relation to the sleeve 31 and slips 26, it will be obvious that the slips will 50 be moved upwardly with relation to the cone 20. Continued downward movement of the cone through the slips causes a radial expansion of 55 said slips, whereby the same are moved into engagement with the inner wall of the well casing B.

When the slips move into their gripping position, as shown in Figure 2, it will be obvious that further downward movement of the packing element 17 which is supported in the cone is also prevented. Therefore, a continued downward 60 movement of the mandrel 10 will cause the shoulder 21 to move away from the lower end of the cone 20 and at the same time the skirt 14 which is fastened to the upper end of the mandrel moves 65 downwardly with said mandrel thereby exerting a pressure on the upper end of the packing element 17. The weight of the mandrel 10, as well as the weight of the tubing string A is transferred to the upper end of the packing element 17 through the skirt 14 and this weight is sufficient 70 to distort the packing element into the position shown in Figure 2. Upon distortion, the outer surface of the packing element 17 moves into engagement with the wall of the well casing B, while the inner surface of said packing ele- 75

ment moves into engagement with the outer surface of the mandrel 10. In other words, when a pressure is applied to the upper end of the element the same will be distorted in both directions radially and the channels 18 on the inner surface of the packing element will be flattened out, as shown in Figure 8. This distortion of the packing element will cause the channels 18 to be closed, whereby fluid cannot pass upwardly through said channels. With such arrangement when the packing element moves to its packing position all by-pass of fluid past said element is prevented. It is noted that the provision of the spaced metallic ring 23 causes the element to be distorted as shown in Figure 2, whereby the effect of plurality of superimposed packing rings or elements is produced.

From the foregoing, it will be seen that the by-pass channels 18 are automatically closed when the packer is moved to a set position. The by-pass channels are formed in the packing element itself thereby eliminating the necessity of forming an auxiliary by-pass for the fluid. The construction of the device is very simple and includes a minimum number of parts. It may be readily set at any desired point within the well casing and may be easily removed by merely lifting the mandrel and engaging the pin 34 in the horizontal leg 33' of the J-slot 33. When this is done, the slips 26 have been retracted from the wall of the casing and the entire device may be removed from said casing. One of the features of the invention is the provision of the by-pass channels which are formed within the packing element itself and which are arranged to be automatically closed when the packing element is distorted into a packing position.

The foregoing description of the invention is explanatory thereof and various changes in the size, shape and materials, as well as in the details of the illustrated construction may be made, within the scope of the appended claims, without departing from the spirit of the invention.

What I claim and desire to secure by Letters Patent is:

1. A well packer including, a support, an annular packing element having vertical channels in its inner wall for by-passing fluid through the element, and means for distorting the packing element into packing position and to close the by-pass channels.

2. A well packer including, a support, an annular flexible packing element mounted on the support and having a plurality of vertical channels in the wall of its bore for by-passing fluid through the element, and means for applying a pressure to the support to distort the same radially in both an inward and outward direction, whereby the inner wall of the element moves into engagement with the support to close the by-pass channels.

3. A well packer including, a support, an annular flexible packing element mounted on the support and having a plurality of vertical channels in the wall of its bore for by-passing fluid through the element, means for applying a pressure to the support to distort the same radially in both an inward and outward direction, whereby the inner wall of the element moves into engagement with the support to close the by-pass channels, and a plurality of rings embedded within the element in spaced relation for reinforcing said element and also for causing the same to distort in such manner as to give the sealing effect of a plurality of superimposed rings.

4. A well packing including, a tubular mandrel, a cone slidable on the mandrel, an annular confining collar secured to the upper end of the mandrel, a flexible packing element surrounding the mandrel and confined between the cone and collar, said element having a vertical channel in the wall of its bore, the cone and collar having openings therein which establish communication between the space exteriorly of the packing element and the passage, whereby when the element 10 is undistorted fluid may flow through the openings and channels to by-pass the element, and means for distorting the element radially whereby the inner wall of said element contacts the mandrel to close the channel. 15

5. A well packing including, a tubular mandrel, a cone slidable on the mandrel, an annular confining collar secured to the upper end of the mandrel, a flexible packing element surrounding the mandrel and confined between the cone and collar, said element having a vertical channel in the wall of its bore, the cone and collar having openings therein which establish communication between the space exteriorly of the packing element and the passage, whereby when the element is 20 undistorted fluid may flow through the openings and channel to by-pass the element, and means for locking the cone against movement in a well casing whereby the weight of the mandrel may be placed on the packing element to distort the 25 same radially and engage the inner wall of the element with the mandrel to close the passage.

6. A well packing including, a tubular mandrel, a cone slidable on the mandrel, an annular confining collar secured to the upper end of the mandrel, a flexible packing element surrounding the mandrel and confined between the cone and collar, said element having a vertical channel in the wall of its bore, the cone and collar having openings therein which establish communication between the space exteriorly of the packing element and the passage, whereby when the element is undistorted fluid may flow through the openings and channel to by-pass the element, means for distorting the element radially whereby the inner wall of said element contacts the mandrel to close the channel, and reinforcing means embedded within the packing element for causing the element to be distorted unevenly throughout its vertical length whereby the element produces the sealing effect of a plurality of 45 superimposed sealing rings. 50

7. A well packing including, a tubular mandrel, a cone slidable on the mandrel, an annular confining collar secured to the upper end of the mandrel, a flexible packing element surrounding the mandrel and confined between the cone and collar, said element having a vertical channel in the wall of its bore, the cone and collar having openings therein which establish communication between the space exteriorly of the packing element and the passage, whereby when the element is undistorted fluid may flow through the openings and channel to by-pass the element, means for locking the cone against movement in a well casing whereby the weight of the mandrel may be placed on the packing element to distort the same radially and engage the inner wall of the element with the mandrel to close the passage, and reinforcing means embedded within the packing element for causing the element to be distorted unevenly throughout its vertical length, whereby the element produces the sealing effect of a plurality of 60 superimposed sealing rings. 65

8. As a sub-combination in a well packer, an elongate flexible packing element having a bore and also having a plurality of vertical channels extending throughout its length and disposed in the wall of said bore.
9. As a sub-combination in a well packer, an elongate flexible packing element having a bore and also having a plurality of vertical channels extending throughout its length and disposed in the wall of said bore, and a plurality of metallic

rings, embedded within the element and spaced throughout the length thereof.

10. A well packer including, a support and a flexible packing sleeve surrounding the support and having means for by-passing fluid thereby, 5 said by-pass means being formed in the material of which the sleeve is constructed, whereby when the sleeve is distorted the by-pass means is automatically closed.

CHARLES S. CRICKMER. 10
